INVENTOR.

William M. Emery

UNITED STATES PATENT OFFICE

169,583

PILLOW

William M. Emery, New Providence, N. J.

Application October 6, 1952, Serial No. 21,736

Term of patent 14 years

(Cl. D3—9)

To all whom it may concern:

Be it known that I, William M. Emery, a citizen of the United States, residing at New Providence, State of New Jersey, have invented a new, original, and ornamental Design for a Pillow, of which the following is a specification, reference being had to the accompanying drawing, forming a part hereof.

Fig. 1 is a plan view of a pillow, showing my new design; while,

Fig. 2 is an edge view thereof.

I claim:

The ornamental design for a pillow, as shown.

WILLIAM M. EMERY.
